UNITED STATES PATENT OFFICE.

EDWIN E. SLICK, OF WESTMONT BOROUGH, PENNSYLVANIA.

REGENERATOR.

1,247,020.

Specification of Letters Patent. Patented Nov. 20, 1917.

Application filed June 23, 1916. Serial No. 105,847.

To all whom it may concern:

Be it known that I, EDWIN E. SLICK, a citizen of the United States, residing in the borough of Westmont, in the county of 5 Cambria and State of Pennsylvania, (whose post-office address is Johnstown, Pennsylvania,) have invented certain new and useful Improvements in Regenerators; and I do hereby declare the following to be a full, 10 clear, and exact description of the invention, such as will enable others skilled in the art to which it appertains to make and use the same.

My invention relates to regenerators 15 which are adapted to conserve the heat and add to the temperature of furnaces, and particularly those which operate at high heats.

The arrangement and construction of my 20 regenerators is of the type known as single surface regenerators, in which the heat of the outgoing gases is applied to and absorbed by the checkers, walls, etc., and given back to the incoming gases from the same 25 surfaces of the checkers, walls, etc., which received the heat.

My apparatus relates to regenerators as 30 above described and not to heat recuperators, which recuperators depend upon the heat transferred or conducted through the materials of which they are composed, the heat being applied to one side of the materials and transmitted through them to the other side whereby the gases are heated.

In order to simplify the description of my 35 invention, I will describe and illustrate it in connection with open hearth steel melting furnaces, but it is, of course, equally applicable to heating furnaces of any and all 40 characters for the purpose of conserving the heat and particularly for furnaces that are fired with gas, oil, tar or other gaseous or vaporizable combustibles and air or oxygen which are adapted to be heated before their 45 combustion.

My invention is particularly applicable to 50 furnaces which are fired with producer gases, which, in accordance with present practice, are delivered to the furnace or the regenerators thereof, at the comparatively high temperatures of from 800 to 1300 degrees, or more, Fahrenheit. When gas of 55 this character is passed through a regenerator which has been previously heated, it becomes highly heated and combines in the furnace with air which has been previously

heated in a similar manner by passing through a regenerator or with oxygen, after which the products of combustion issue from the furnace hearth and pass through other 60 similar regenerators in order to give to them the heat remaining in said products of combustion, which heat is utilized, on the reversal of the currents in the furnace, for heating the air and combustible gases of the 65 reversed currents. As, however, producer gas, when going into its regenerator, has, under the condition stated, a temperature which for the purposes of explanation herein will be said to be about 1200 degrees Fahr- 70 enheit, this gas makes the coolest part of the regenerator checkers, or that part remote from the furnace, of a temperature about equal to that of the gas, or slightly less than 1200 degrees. As, according to the old practice, gas checkers have a minimum temperature of 1200 degrees, or higher, owing to the previous influx of hot gas, they cannot, of course, abstract heat from the gaseous products of combustion to an extent such as to 75 make these gases of combustion pass to the stack or atmosphere at any less temperature than the said 1200 degrees, or thereabout, with the result that in such a case the combustion gases escape to the atmosphere at 80 very high temperatures and carry with them 85 large and valuable amounts of heat.

It is the purpose of my invention to conserve this heat which would otherwise be wasted and I accomplish this as follows:— 90 A furnace provided with the usual pairs of air and gas regenerators is also provided with a pair of auxiliary regenerators, one in connection with each pair of main regenerators, so constructed that said auxiliary 95 regenerator and its contained checkers is heated by the outgoing gases or products of combustion, which, after passing through the ordinary regenerators, pass through the said auxiliary regenerator. When the currents of gases are reversed in the furnace, the auxiliary regenerator, which has been previously heated by the products of combustion, is supplied with air, which is at or about atmospheric temperature, which air 100 is introduced at substantially the same location as that of the introduction of the previously heated products of combustion and flows through the first portion of my auxiliary regenerator in the same direction. 105 The air then travels through another portion of the auxiliary regenerator which, how-

2

ever, is an extension of the usual air regenerator, in a direction opposite to that of the previous travel of the products of combustion, which further adds to the pre-heating of the air, and thence it issues into the usual air regenerator where it is finally heated prior to its emergence from the air ports to meet the gases for combustion. Part of the auxiliary regenerator is heated by the outgoing gases which issue from the air regenerator and another portion of the auxiliary regenerator is heated by the combustion of gases which pass out of the gas regenerator. The auxiliary regenerators are used only for heating air, on the reversal of the currents, for the reason that the incoming air is cooler than the gas and needs more heat and said air also cools the auxiliary regenerator to make it receptive to further heat exchange upon the next reversal, whereas the producer gas is delivered to the furnace at such a heat as not to need this auxiliary regeneration. The incoming gas at a temperature of about 1200 degrees Fahrenheit, should not be introduced into a first or auxiliary regenerator, as on reversal the heat of combustion gases equal to its heat, viz: 1200 degrees or more, would be lost. I may construct my auxiliary regenerator with the usual filling of silica, clay or other brick stacked crosswise of each other to allow numerous passages for the flow of gases and of mass sufficient to absorb the heat from the products of combustion and return it to the air after reversal. I may, however, make my checkers of cast iron or steel which have a much higher conductivity than bricks, and which metals receive and give off heat with greater ease and speed.

Having thus given a general description of my invention, I will now, in order to make the matter more clear, refer to the annexed sheet of drawings in which like characters refer to like parts.

Figure 1 is a longitudinal sectional elevation of the upper portion of an open hearth furnace adapted to embody my invention, this view being taken on the line I—I of Fig. 3; Fig. 2 is a sectional plan of my construction taken through the regenerators, showing the producer gas pipe in plan; Fig. 3 is a transverse sectional elevation taken on the line III—III of Fig. 2; Fig. 4 is a vertical cross sectional elevation of one of the gas admission valves; and Fig. 5 is a vertical sectional elevation of one of the air inlet valves. Figs. 1, 4 and 5 are drawn on a somewhat larger scale than Figs. 2 and 3.

Although the furnace is substantially symmetrical about its transverse center line, the parts on opposite sides thereof have been given different numbers for clearness of description, particularly when referring to the flow of gases.

Referring now to the characters of reference on the drawings, the body or superstructure of the furnace generally, is indicated as 1, the hearth as 2 and the roof as 3.

Referring now to the portion of the furnace on the left hand side of the drawing, the air entering port is 4, the gas entering port is 5, the upwardly extending flue connecting the air regenerator with the air port is 6, the upwardly extending flue connecting the gas regenerator with the gas port is 7, the slag pocket connected with the gas port is 8, the main air regenerator is 9, the main gas regenerator is 10. The various portions of my auxiliary regenerator are designated as 11, 12 and 13 respectively, these portions 11, 12 and 13 representing the portions or sections of one of the auxiliary regenerators, the arrangement and construction of which is such that the products of combustion or the air to be heated always pass in the same direction through the sections 11 and 12, while the air to be heated by the section 13 passes in a reverse direction from that of the products of combustion, the gas entering valve is 14, the air entering valve is 15, a controlling valve or damper is 16 and another controlling valve or damper is 17, and the slag pocket connected with the air flues is 33. 95

Referring now to the similar portions of the construction on the right hand side of the drawing, the air entering port is 18, the gas entering port is 19, the upwardly extending flue connecting the air regenerator with the air port is 20, the upwardly extending flue connecting the gas regenerator with the gas port is 21, the slag pocket connected with the gas flues is 22, the slag pocket connected with the air flues is 32, the main gas regenerator is 23, the main air regenerator is 24, the various portions of my auxiliary regenerator are 25, 26 and 27 respectively, these portions 25, 26 and 27 representing the portions or sections of one of the auxiliary regenerators, the arrangement and construction of which is such that the products of combustion or the air to be heated always pass in the same direction through the sections 25 and 26, while the air to be heated by the section 27 passes in a reverse direction from that of the products of combustion, the gas inlet valve is 28, the air inlet valve is 29, a controlling valve or damper is 30 and another controlling valve or damper is 31. 110

Referring now to Figs. 4 and 5: Fig. 4 illustrates a form of gas inlet valve of which there are two to the furnace, namely:—one numbered 14 on the left hand side and one numbered 28 on the right hand side, each of these being provided with a mushroom valve 34 and an operating rod 35 by which it may be raised or lowered; referring now to Fig. 5, this represents the general con- 130

struction of the air inlet valves of which there are two to the furnace, namely: one numbered 15 and one numbered 29, each of which is provided with a mushroom valve 36 and an operating rod 37 by which it may be raised or lowered and an air intake pipe 38, which pipe may either be connected directly to the atmosphere or to a suitable source of air under pressure from a 10 fan blower or other apparatus, not shown. Producer gas, or other combustible gas, is supplied to these valves by means of the branch pipes 41, which in turn are supplied by the main gas pipe 40 which is connected to gas producers or other sources of gas or similar combustibles. 39 represents the stack which may be of any height desired to give the necessary draft, or if the heat of the final products of combustion 20 after passing through my auxiliary regenerators, is so low that the stack draft would not operate, I may provide an exhaust fan or other apparatus to discharge the products of combustion into the stack and thus 25 maintain the necessary draft.

The main regenerators Nos. 9, 10, 23 and 24 may be filled with a cellular structure, composed of clay brick, silica brick or other refractory materials, as these and their upper portions particularly are subjected to the very high heat of the escaping gases of combustion; and I may also fill the various portions of my auxiliary regenerators 11, 12, 13, 25, 26 and 27 with similar bricks; but as 35 the temperatures in these auxiliary regenerators are very much less than in the main regenerators, I may prefer to fill these with metal checkers composed of any suitable metal such as cast iron, special cast iron 40 adapted to withstand heat and oxidation, steel of various qualities, or in fact any other metal, as metals have a greater capacity for receiving and giving off heat than bricks. The checker work of these regenerators may be laid up loosely in various manners, in order to provide the cellular structure and of mass and quantity sufficient to receive and give up heat as required. I provide openings between the 45 checkers to form passages for the incoming air and gas and the outgoing products of combustion.

As illustrated in the drawings, I prefer to introduce the incoming air and gases into 55 the bottoms of the regenerators so that the heating and cooling effects take place more readily, but this may be arranged otherwise, if desired.

My arrangement of regenerators, auxiliary regenerators, the valves and dampers therefor, and the manner and direction of flow therethrough, conduce to simplicity, compactness, ease and economy of construction and operation.

85 The various portions of my auxiliary

regenerator are provided with spaces between the same, as illustrated on the drawings to provide easy access for the purpose of cleaning and repairing.

Having thus given a description of my invention, I will now describe its operation.

Assuming now that the gases travel through the furnace from left to right, the gas valve 14 is open, the air valve 15 is also open, the stop valve 16 is closed and in its downward position, the stop valve 17 is also closed in its downward position, the stop valves 30 and 31 are up in their open positions, the gas valve 28 is down in its closed position and the air inlet valve 29 is down in its closed position, whereupon the flow of the gases is as indicated by the arrows. It will thus be seen that the air at atmospheric temperature which enters the air inlet valve 15 is first heated by passage through the auxiliary regenerator 11, 12 and 13, the direction of the flow of the air in the portions 11 and 12 being in the same direction as that of the products of combustion which previously passed through this portion of the auxiliary regenerator and heated it. The air continues through the portions 12 and 13 of the auxiliary regenerator where it is further heated and passes thence into the main air regenerator 9, where it is finally heated and passes thence through the slag pocket 33 and thence upwardly through the flues 6 and into the furnace through the air port 4. At the same time the gas which enters the valve 14, passes directly thence into the main gas regenerator 10, then through the slag pocket 8 and upwardly through the flue 7 and into the furnace through the gas port 5, and on issuing from the gas port it meets the heated air coming from the port 4 and combustion takes place within the furnace. The products of combustion pass out through the other end of the furnace, through the ports 18 and 19, downwardly through the flues 20 and 21, through the slag pockets 22 and 32, a part going through the gas regenerator 23 and a part through the air regenerator 24, giving up a large portion of heat to said regenerators, and then pass out through the portions 25, 26 and 27 of the auxiliary regenerator in the directions indicated by the arrows, whereby the gaseous products of combustion yield a further portion of their heat to the auxiliary regenerator in such a way that as they cool down they leave the heat in these auxiliary regenerators which would otherwise be wasted. The thoroughly cooled gases of combustion now pass through the valve 31 and into the stack 39 where they escape into the atmosphere. During this operation, gas is supplied through the main pipe 40 and through branch pipe 41 to the gas valve 14, and air is supplied to the air valve 15 through the pipe 38, which, as

before stated, is connected with the atmosphere or with a source of air under pressure. After the furnace is operated in the manner described for the proper or desired 5 length of time, the valves which were closed are now opened, and those which were opened are now closed, whereupon a reversal of currents takes place and the gases flow through the furnace from right to left and 10 in directions opposite to the arrows on the drawings, except in the portions 25 and 26 of the auxiliary regenerator, in which portions the heating gases, and on reversal the air to be heated, flow in the same direction 15 as indicated by the arrows, in the same manner previously described in connection with the portions 11 and 12 of the other auxiliary regenerator.

The main air regenerator 9 and the directly connected regenerator 13 may be considered as one regenerator, as both of these are reversing regenerators, placed end to end and through which the combustion gases pass in one direction and the incoming air 25 in the other direction. The gas regenerator 10, however, and the directly connected auxiliary regenerator 11 and 12 cannot be so considered, for the reason that they do not act together in the manner just described, 30 but the auxiliary regenerator 11 and 12 is cut off from the gas regenerator upon reversal of the currents in the other portions and is then used for heating the air, the portions 11 and 12 of the auxiliary regenerator not being reversed, and this is 35 similarly true of the companion portions on the other side, namely:—25 and 26.

Although I have shown and described my improvements in considerable detail, I do 40 not wish to be limited to the exact and specific details shown and described, but may use such substitutions, modifications or equivalents thereof, as are embraced within the scope of my invention, or as pointed out 45 in the claims.

Having thus described my invention, what I claim and desire to secure by Letters Patent is:—

1. In a regenerative furnace, an air and a 50 gas reversing regenerator connected to each end thereof, a sectional auxiliary regenerator connected to each of the pairs of said reversing regenerators, means for passing air through portions of said auxiliary regenerator in the same direction as the products of combustion and through other portions in a reverse direction into its connecting main air regenerator, substantially as described.

2. In a regenerative furnace, a pair of reversing regenerators connected with each end of said furnace, a sectional auxiliary regenerator connected with each of said pairs of regenerators, means for passing 65 incoming air through portions of said auxil-

iary regenerator in the same direction and through other portions in the reverse direction to the flow of the combustion gases, said auxiliary regenerator being provided with metal checkers.

3. In a regenerative furnace, a reversing air, a reversing gas generator and an auxiliary regenerator connected with each end thereof, regulating means adapted to control the discharge of the combustion gases 75 from each pair of air and gas regenerators through said auxiliary regenerator, and means for passing incoming air through portions of said auxiliary regenerator in the same direction as the products of combustion and through other portions of the same in the reverse direction, thence into its connecting main air regenerator.

4. In a regenerative furnace, a reversing air regenerator and a reversing gas regenerator, each connected with each end thereof, a sectional auxiliary regenerator adapted to be connected with each pair of reversing gas and air regenerators, means for passing air through one portion of said auxiliary 90 regenerator in the same direction as that previously taken by the products of combustion and through other portions in the same direction into its connecting air regenerator, said auxiliary regenerator being provided 95 with metal checkers.

5. The method of operating a regenerative gas furnace which consists in preheating the air by successive passage through a series of regenerators in the same and reverse directions to the previous flow of the combustion gases therethrough, and heating the combustible gases by flow through a single reversing regenerator and passing the products of combustion through air and gas 100 regenerators and an auxiliary regenerator at the other end of the furnace.

6. The method of operating a regenerative gas furnace which consists in preheating the air by successive passage through a 110 series of regenerators in the same and in reverse direction to the previous flow of the combustion gases therethrough, heating the combustible gases by flow through a reversing regenerator in a direction opposite to the previous flow of combustion gases therethrough, passing the products of combustion through the air and gas regenerators, and through an auxiliary regenerator, and then reversing the direction of flow of the gases 115 except in a portion of the auxiliary regenerator.

7. In a regenerative furnace a pair of reversing regenerators for air and gas, and an auxiliary regenerator, part of which is 125 non-reversing and adapted to be heated by the products of combustion, and means for passing combustion air through said non-reversing portion thence through the reversing air regenerator.

8. In a regenerative furnace, a pair of reversing regenerators for air and gas connecting with one end thereof, said air regenerator being also connected with a reversing portion of an auxiliary regenerator, and said gas regenerator being connected with a nonreversing portion of said auxiliary regenerator, and means for passing incoming air through the nonreversing portion of the auxiliary regenerator, and thence through the reversing portion of said auxiliary air regenerator and thence into the air regenerator aforesaid.

9. In a regenerative furnace, pairs of reversing regenerators for gas and air connected to opposite ends thereof, an auxiliary regenerator interposed between each pair and the stack and having branches connected to each regenerator of the pair, means for cutting off one branch from its corresponding regenerator and for supplying air to said branch, and means for cutting off each auxiliary regenerator from the stack.

In testimony whereof I hereunto affix my signature.

EDWIN E. SLICK.
